UNITED STATES PATENT OFFICE.

ARTHUR LOWENSTEIN, OF CHICAGO, ILLINOIS.

STEAMING OF OILS, &c.

1,274,175.

Specification of Letters Patent. Patented July 30, 1918.

No Drawing.

Application filed August 28, 1916. Serial No. 117,288.

To all whom it may concern:

Be it known that I, ARTHUR LOWENSTEIN, a citizen of the United States, residing at Chicago, in the county of Cook and State of Illinois, have invented a new and useful Improvement in the Steaming of Oils, &c., of which the following is a specification.

My invention relates to certain new and useful improvements in the heat treatment of such products as fatty acids and their glycerids. More particularly I am concerned with the heating of such materials for the purpose of deodorizing (in the case of the oils) and distilling (in the case of the acids), by direct contact with steam, the invention consisting primarily in the use of superheated steam of very low pressure for these purposes. The objects of the invention are, in general, to produce a technically superior product, and to reduce the cost of the treatment.

In the deodorization and distillation of cottonseed oil and other oils, fats, waxes and fatty acids, it has been customary to place the product in a closed vertical cylindrical tank provided with a vapor outlet at the top, internal closed coils of steam-pipe for the initial heating of the oil, up to the desired temperature, and a perforate spider or other distributor in the bottom for the admission of dry and saturated steam directly into the tank during the treating period proper. The process of deodorization as thus carried out usually required from six to eight hours to produce the desired result and was exceedingly wasteful of steam. Although a great deal of oil is still processed in this manner, two major improvements have been widely introduced which effect a considerable saving of time and of steam. The first improvement consisted in operating the refining tank or still under a vacuum of from 20 to 26" of mercury. The second improvement consisted in substituting for the dry and saturated or normal live steam, superheated steam. Such superheated steam however, as heretofore used, has invariably been superheated at relatively high pressures—usually at the common boiler-pressure of 60-150 lbs. per in², the ordinary superheater installation made use of in power plant practice having been employed for the purpose. In the use of this high pressure superheated steam in deodorizing and distilling, there is necessarily a great expansion of the steam as it enters the liquid body of material under

treatment. I do not find that such expansion serves any useful purpose but on the contrary I believe it to be undesirable from every standpoint. Thus, it is quite clear from 60 the laws of physics that in the expansion of any gas heat is necessarily absorbed, the absorption of thermal units being proportionate to the expansion. A considerable fraction of the total heat of the superheated 65 steam is therefore dissipated in the act of expansion, being converted into kinetic energy or velocity energy, with a consequent drop in temperature of the steam, and without any counterbalancing benefit to the 70 process from the needlessly high outflow velocity attained. Furthermore, the temperature effective for the treatment of the product is probably as low as or even lower than the final expanded temperature of the 75 steam, and the initial superheat temperature must therefore be so far above this expanded temperature as to balance the drop which occurs in expansion. It follows therefore that the initial temperature of the steam is 80 substantially above its effective temperature, and if the latter temperature is high enough to secure the desired result of deodorization or distillation in the shortest practicable time, the initial temperature will be dangerous 85 and capable of injuring that portion of the product which may be exposed to it, as for instance the film of liquid adjacent the exit nozzle or perforation.

I find that these conclusions are fully confirmed by the practice of my process. Not only is there a great saving of heat in the use of low pressure superheated steam in place of relatively high pressure steam, but the product, that is the deodorized oil or 95 distilled acid, is noticeably superior in color to the product produced by the known processes.

The greatest economy may be effected by my process where it is possible to make use 100 of exhaust steam, that is steam which has been expanded down to a low pressure in the performance of useful work. It is then only necessary to install suitable separators or traps for removing water, oil or other 105 impurities, and such steam may be led into superheaters of proper design and capacity, and fed from the latter directly to the stills or deodorizing tanks, the traps and superheaters being all the additional equipment 110 required and the steam being a waste product. Where exhaust steam is sufficient quan-

5 tity is not available it may be supplemented or replaced by live steam from the ordinary power boilers, this steam being first expanded and then superheated, or special low-pressure boilers may be installed and coupled directly with the superheater. In each case, even where live steam is expanded without doing work, there is a considerable saving in heat, and the low-pressure superheated 10 steam, regardless of its source, produces a more nearly neutral and perfect refined or distilled product than does the high-pressure steam. The exact pressure of the steam which should be used for obtaining the full 15 benefits of my invention will of course vary within reasonable limits according to the mechanical conditions met with in any specific installation. In my work to date I have made use of steam pressures of from 20 two to six pounds per in².

In order that the essential principles of my invention may be fully understood I will give one example of a process in accordance with the invention. A charge of twenty 25 thousand pounds of cottonseed oil is let into a tank of the usual form above described. By means of the closed steam coils immersed in the oil within the tank the temperature is brought up to approximately 30 250° F. Exhaust steam, properly purified, and of a pressure of about 2½ lbs. per in² is led through a superheater in which it reaches a temperature of about 500° F., thence into the distributing spider at the base of the tank. A vacuum of about 25" of mercury is preferably maintained on the top of the oil (although this is not essential to my process, which is equally serviceable when operating at atmosphere pressure).

In from one and one half to seven hours (depending upon the nature of the oil and upon the use of a vacuum or atmospheric pressure) the treatment will be finished and the product will be of the highest grade and

more nearly neutral than the products obtained by similar treatment according to the known processes. 45

Although I have described in considerable detail one specific example of a process according to my invention, it will be understood that this is illustrative only and for the purpose of making the invention more clear, and the invention is not to be regarded as limited in any way either by the foregoing particular description of the theories which I entertain and to which I attribute the benefits of the process or by the specific example given, except in so far as such limitations are included within the terms of the accompanying claims, in which 50 it is my intention to claim all novelty inherent in my invention as broadly as is permissible in view of the prior art. 55

What I claim as new and desire to secure by Letters Patent is: 60

1. The steps in the process of heat-treating oils, fats, waxes, fatty acids and like products at pressures not substantially exceeding atmospheric which consist in superheating steam while at a relatively low pressure to a temperature sufficient to maintain the steam in a superheated condition after its expansion, and subjecting such products to the direct heating effect of such low-pressure superheated steam, whereby the expansion of the steam during the treatment is relatively small. 75

2. The steps in the process of distilling fatty acids or deodorizing glycerids thereof at pressures not substantially exceeding atmospheric which consist in superheating steam to a temperature not substantially below 500° F. while at a pressure not substantially exceeding six pounds per square inch, and subjecting the said materials in the 80 liquid state to the direct action of a current of such superheated steam. 85

ARTHUR LOWENSTEIN.
